CIRCUIT INTERRUPTING FUSE

Jean Nivoix, La Plaine Saint-Denis, France, assignor to Societe Anonyme dite: Forges et Ateliers de Constructions Electriques de Jeumont, Paris, a corporation of France

Application September 10, 1951, Serial No. 245,805

Claims priority, application France
September 22, 1950

5 Claims. (Cl. 200—120)

1

The present invention relates to circuit interrupting fuses. These fuses may be of the so-called cartridge type and may comprise one or more fusible elements which may or may not be associated with quenching or arc-extinguishing material. More particularly, the invention has especial relation to circuit interrupting fuses of the renewable element type.

A primary object of the present invention is to facilitate the extinguishment of the arc which accompanies circuit interruption. A further object of the invention is to prevent deterioration of the fixed contacts to which the renewable fusible elements are attached.

In conventional fuses of the type here involved, the fusible elements (rods, strips, wires, etc.) are fixed between securing members of any suitable type or are otherwise attached to these members, and the latter—which may also be designated fixed contacts—are covered and protected from the arc generated upon circuit interruption by fusion of the fusible element, by means of one or more incombustible and insulating liners or washers of mica, asbestos or the like, through which each fusible element passes.

In such conventional arrangement, when the short circuiting current is high, the fusible element is completely volatilized and the arc extends to the fixed contacts, notwithstanding the aforementioned liners or washers. This is bound up with a number of defects: on the one hand, the fixed contacts are seriously damaged and frequently are incapable of further use; on the other hand, the arc may even penetrate through the said members to the exterior, which is very dangerous; finally, even if the last-mentioned eventuality does not occur, the partial volatilization of the securing members or fixed contacts generates an excessive amount of metal vapor which markedly lowers the circuit breaking capacity of the fuse and produces a risk of explosion.

The present invention provides simple and efficient means for obviating these defects and for obtaining the afore-enumerated objects. In accordance with the invention, briefly stated, the fusible elements (rods, strips, wires, bars, etc.) comprise bends arranged so that the arcs which are propagated along such elements encounter a transverse insulating partition or partitions at a point sufficiently distant from the openings through which undesirable propagation can take place, so that excessive elongation of the arcs is prevented.

2

With the above and other objects in view, which will become apparent from the detailed description which follows, reference is made to the accompanying sheet of drawings wherein several presently preferred embodiments of the invention are diagrammatically illustrated. Conventional cartridge fuse structure has, for the sake of clearness, not been shown. On the said sheet:

Fig. 1 is a diagrammatical view, partly in section and partly in elevation of one embodiment of the invention;

Fig. 2 is a similar view of a second embodiment of the invention; and

Fig. 3 is a similar view of still another embodiment of the invention.

Referring first to the embodiment according to Fig. 1, reference character F_1 designates a fusible element, which may take the form of a strip or of a wire or the like of fusible metal or alloy (e. g. silver, etc.). Element F_1 is secured in any suitable and per se conventional manner to securing members or fixed contact pieces A, B and A_1 , B_1 . A liner, baffle plate or washer R lines the inner surface of contact pieces A, B and a similar member R_1 lines the inner surface of contact pieces A_1 , B_1 , the members R and R_1 being perforated so that element F_1 may pass therethrough. Members R and R_1 are advantageously made of incombustible or refractory insulating material such as mica, asbestos and the like.

Arc-stopping baffle plates or washers R' and R'_1 are provided according to the invention to prevent an arc, generated upon the fusion of element F_1 at a hot intermediate point thereof from penetrating through to the perforation in liner R or R_1 . For mounting the members R' and R'_1 , fusible element F_1 is provided adjacent each end with a pair of spaced bends x and y, each said pair of bends being connected by a

short rectilinear portion extending substantially at right angles to the free portions of element F_1 (which are shown as substantially rectilinear). Each auxiliary washer R' and R'_1 is so disposed on element F_1 that a lateral surface of the washer is in contact with the adjacent short rectilinear portion extending between the adjacent bends x and y. As shown in Fig. 1, the washers R' and R'_1 are perforated eccentrically (i. e. are offset relative to the perforations in main washers R and R' to the extent of the said short rectilinear portion).

With this relationship of parts, any arc which is engendered due to the rupture of a free portion of the fusible element is effectively stopped

at the washers R' and R'_1 and is thus prevented from extending beyond the ends of the said free portion of the said element. At worst—if the interrupted current happens to be very strong—the resultant arc may possibly partially volatilize the two portions of the fusible element which are disposed between the pairs of washers R , R' and R_1 , R'_1 . In this way, the fixed contacts A , B and A_1 , B_1 are effectively and reliably protected from deleterious effects of the arc.

If the circuit interrupting fuse is of the type requiring one or more intermediate partitions R_2 (which may be of the same refractory material as the previously mentioned washers)—as where it is desirable for any reason to divide up the 15 interior of the fuse into smaller spaces—such intermediate partition or partitions may be retained in position with the aid of juxtaposed intermediate folds P , P formed in element F_1 , as shown in Fig. 1 of the drawings.

In certain cases, it is possible within the scope of the present invention to dispense with the washers R' and R'_1 . A relationship of parts according to this invention wherein the latter are omitted is shown in Fig. 2. This relationship of parts involves an intermediate partition R_2 , of the character described in the preceding paragraph. Instead of disposing the said intermediate partition between two intermediate folds P , P in the element F_2 , it is disposed between one such fold P which contacts the partition R_2 on one side thereof and an intermediate short rectilinear portion F of element F_2 on the other side thereof. Portion F is disposed essentially at a right angle to the free portions of element F_2 and extends in contact with the adjacent lateral surface of partition R_2 . Bends x and y are formed adjacent each end of the fusible element F_2 , as in the embodiment according to Fig. 1, and the resulting short rectilinear portions lie in close contact on one side thereof with the adjacent surface of the juxtaposed washer R or R_1 , as shown in Fig. 2.

With this construction, an arc engendered on one side of the partition R_2 is effectively prevented from extending over to the other side of the partition. The small rectilinear portions between bends x and y also minimize elongation of the arc to and through the perforations of the washers R and R_1 .

Where very strong currents are likely to be encountered, propagation of the arc is deterred according to the invention by an expedient which, contrary to that of Fig. 2, involves increasing the number of protective washers and intermediate partitions. Such a relationship of parts is shown in Fig. 3, according to which each of the several bends formed in the fusible element F_3 (which may, in this embodiment, take the form of a strip) is completely enclosed in a structure consisting of a plurality (shown on the drawing, by way of example, as three) of spaced groups of washers R_3 , R_4 or R_5 which, like the previously described washers, are made of suitable refractory material, such as mica, asbestos or the like. These multiple washers may be fastened in assembled groups by any suitable means, for example with the aid of a suitable cement or the like, augmented if desired by one or more additional folds P , as shown in Fig. 3.

While the portions of the fusible elements which are not parallel to the general axis thereof, have been shown as being essentially at right angles thereto, it will be understood that such portions may extend at various angles. It will 75

also be understood that various other minor changes may be made without departing from the spirit and scope of the invention.

Having thus disclosed the invention, what is claimed is:

1. A circuit-interrupting fuse having terminal contacts, a fusible element with free portions extending between said contacts, insulating refractory plates disposed between said contacts and provided with perforations through which said element passes, said portions being laterally offset from said perforations, said element being provided with a plurality of spaced bends defining rectilinear portions therebetween arranged at an angle relative to said free portions, and each of said rectilinear portions being in contact with a lateral surface of one of said refractory plates, whereby the points where an arc, engendered upon fusion of said free portions, may reach said refractory plates are spaced from the perforations in said plates.

2. A circuit-interrupting fuse having terminal contacts, a fusible element with free portions extending between said contacts, an insulating refractory liner for each of said contacts and provided with a perforation through which said element passes, an insulating refractory plate adjacent each liner and provided with a perforation through which said element passes, the perforations of the liners being laterally offset with respect to the perforations of the plates, said portions being correspondingly laterally offset with respect to said perforations of said plates, said element being provided with a plurality of pairs of spaced bends adjacent, each pair defining a rectilinear portion therebetween arranged at an angle relative to said free portions, and each of said rectilinear portions being in contact on one side with the lateral surface of one of said refractory liners and on the other side with one of said refractory plates, whereby the points where an arc, engendered upon fusion of said free portions, may reach said refractory plates are spaced from the perforations in said plates.

45. 3. A circuit-interrupting fuse according to claim 2, comprising a further refractory plate between each adjacent liner and plate.

4. A circuit-interrupting fuse according to claim 1, comprising an additional refractory partition located between the ends of the fusible element and having a perforation for the passage of said element, said perforation being laterally offset with respect to the perforations of said plates, said partition being in contact, along at least one wall thereof, with an adjacent portion of said fusible element.

5. A circuit-interrupting fuse according to claim 4, wherein said additional refractory partition comprises a plurality of adjacent perforated washers.
